UNITED STATES PATENT OFFICE.

BENNETT MYERS, OF GROVEPORT, OHIO.

WIRE-STRETCHER.

SPECIFICATION forming part of Letters Patent No. 716,080, dated December 16, 1902.

Application filed April 26, 1902. Serial No. 104,637. (No model.)

To all whom it may concern:

Be it known that I, BENNETT MYERS, a citizen of the United States, and a resident of Groveport, in the county of Pickaway and State of Ohio, have invented a new and Improved Wire-Stretcher, of which the following is a full, clear, and exact description.

The purpose of my invention is to provide a simple, durable, and effective form of wire-stretcher and one which can be conveniently applied and operated and which in its operation will not injure a smooth or decorated post.

Another purpose of the invention is to provide a wire-stretcher with jaws having straight, smooth, or rough faces which grasp the wire simultaneously their entire length with equal pressure throughout, thus preventing the wire from being kinked or nicked, and also to so construct the device that it may be successfully operated upon wire of any size and may be readily brought into action to take hold of the wire or to release the same.

The invention consists in the novel construction and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a plan view of the device in its normal position in contact with the post. Fig. 2 is a sectional view of the device, the section being taken on the line 2 2 of Fig. 3. Fig. 3 is a longitudinal central section taken practically on the line 3 3 of Fig. 1, and Fig. 4 is a plan view of the device in action and a plan view of a post against which it has bearing.

The handle-section A of the device may be made of any desired length and is transversely widened at its head end a. At the terminal of the head end a of the handle adjoining segmental projections 10 and 11 are formed on each side of the handle, the projection 10 extending farther outward than the projection 11 and is of greater radius, and said head end of the handle is further provided with a chamber 12, open at the outer end and at the sides of the handle, as is shown in Fig. 2. The lower jaw B is made integral with a

sleeve 13, said jaw extending beyond opposite sides of the sleeve, as is shown in Fig. 3, and the outer or gripping section of the jaw is straight and smooth. An opening 14, preferably rectangular and of greater length than width, is made in the central portion of the said lower jaw B, dividing it into two sections b and b', which opening continues into the sleeve 13, forming a chamber 15 therein, which chamber extends through the rear or inner end of the sleeve at one side, but stops short of its rear end at the opposite side, forming an inner shoulder 16, as is illustrated in Fig. 2. A tongue 17, rectangular in cross-section, extends from the closed rear end of the sleeve 13 centrally between its sides, and at the opposite edge of the sleeve an opposing closing-strip 18 extends from the sleeve, the outer and inner surfaces of the strip being respectively flush with the outer surface of the sleeve and the end wall of its chamber. In fact, the strip 18 corresponds to the tongue 17, being called a "strip," because it is thinner from front to rear than the tongue 17, and said strip and said tongue constitute the front and rear portions of the inner end of the sleeve 13 or that end which is adjacent to the handle of the device.

Two adjoining segmental recesses 19 and 20 are made in the rear edge of the sleeve at each side face, the recess 19 being of greater radius than the recess 20, and it extends outwardly beyond it, as is shown in Fig. 4. The larger recess 19 corresponds in radius to the projection 10 from the handle, which projection it is adapted to receive, and the recess 19 extends from one side edge of the sleeve to a point near the tongue 17. The recesses 20 are at each side face of the tongue 17, extending to the opposite side edge of the sleeve, and these recesses 20 are of the same radius as the handle projection 11 and are adapted to receive such projection. The side faces of the sleeves at the recesses 19 and 20 are reinforced by ribs 21.

The upper jaw C is flat at its under or gripping surface and corresponds in size to the size of the lower jaw B. It is divided into two sections c and c' by a central bar or shank 22, having an extension 23 at one side, forming a shoulder 24 at the opposite side, as is shown in Fig. 2, and said upper jaw car-

ries an integral head 25, having a straight smooth bearing-face 26 flush with that end of the upper jaw C adjacent to which the extension 23 of the shank 22 is located.

5 The parts are assembled as follows: The tongue 17 of the sleeve 13 and the closing-strip 18 of the sleeve are made to enter the chamber 12 in the head portion of the handle until the projections 10 and 11 for the handle 10 have fully entered the recesses 19 and 20 in the sleeve 13. Next the shank 22 of the upper jaw is passed through the opening 14 in the lower jaw B into the chamber 15 of the sleeve 13, the extension 23 of the shank passing into the through-opening in said chamber, as is shown in Fig. 2. The two jaws are left spaced a predetermined distance apart, likewise the shoulder 16 in the sleeve and the shoulder 24 of the shank 22 of the upper jaw, 20 as the two shoulders will be opposite each other, as is also shown in Fig. 2. Finally a pin 27 is passed through the projection 10 of the handle at a central point with respect to its radius and through the extension from the 25 shank of the upper jaw, connecting said upper jaw with the handle, and a second pin 28 is similarly passed through the handle projection 11 and through the tongue 17, connected with the lower jaw, thus connecting 30 said lower jaw with the handle.

It will be observed that a line drawn through the center of the pin 27 will not strike the opposite pin 28, but will pass forward of said pin.

35 In operation the handle being straight the smooth surface of the head 25 of the upper jaw C is placed against a post D in a manner to bring the space between the jaws B and C over the wire, which will be received in such 40 space. Then by moving the handle outward or in direction of the recesses 20 the jaws are brought in direction of each other to a firm clamping engagement with the wire and may be so held while any desired force is exerted 45 without injury to the wire, as the jaws clamp the wire uniformly throughout their length. This device will hold the wire without slipping and will let loose the wire upon straightening the handle without flattening the wire.

50 The advantage of having two sets of jaws is great, as the wire can be caught under all conditions, the jaws are less liable to be sprung, and if this should happen to one set of jaws it is quickly rectified by bringing the 55 opposite set into operation. The principal use of the stretcher is for closing up the ends of woven-wire fence and stretching the wire from the stretcher-bar to the end post after the rest of the fence has been stretched by a 60 stretcher-bar and jacks.

The device is also very useful for stretching barbed wire on fences, or any other kind of wire, or wherever it is desirable to stretch wire with a hand-stretcher. The device is 65 preferably made of malleable or wrought iron; but the clamping-surfaces of the jaws are faced with steel, as is illustrated.

Having thus described my invention, I claim as new and desire to secure by Letters Patent—

1. In a wire-stretcher, an upper and a lower jaw, an extension from each of the jaws at an angle to their gripping-surfaces, the extensions of the upper jaw being loosely passed through the lower jaw to a parallel position 75 with its extension, a rocking handle normally in the same horizontal plane with the jaws, and pivotal connections between the handle and each of the said extensions from the jaws, the said connections being in the same horizontal plane but one in advance of the other as described, and segmental projections from the handle, in which projections 80 said pivotal connections are located, the said projections being arranged for movement 85 within segmental recesses formed in the side faces of the support for the lower jaw, substantially as described.

2. In a wire-stretcher, an upper and a lower set of jaws, an extension from each set of jaws 90 at a right angle thereto, the extensions from the upper jaw being loosely passed through the lower jaw to a point parallel with its extension, a sleeve forming a portion of the lower jaw and provided with adjacent segmental recesses of different radii, a handle recessed to receive the extensions of both jaws and adapted to rock in a direction at right angles to the direction of the movement of the jaws, segmental projections of different radii extending 95 from the handle and into the said segmental recess, connections substantially as described, between the jaws at the said segmental recesses and the projections from the handle, whereby through the movement of the 100 handle to open and close the jaws, and a bearing-head secured to the outer jaw, extending 105 outwardly therefrom, as set forth.

3. In wire-stretchers, the combination with a lower jaw provided with an attached sleeve, 110 said sleeve having adjoining segmental recesses in its rear end, one in advance of the other and of different radii, a tongue projecting from the recessed end of the sleeve at one side, an upper jaw having parallel movement 115 with relation to the lower jaw, a bearing-head fast to the outer face of the upper jaw, and a shank extending from the gripping-face of the upper jaw, extending loosely through the sleeve parallel with the tongue of the sleeve, 120 the tongue being opposite one of the sleeve-recesses and the shank opposite the adjoining recess, of a handle provided with a chamber to receive said tongue and said shank and also provided with adjacent segmental projections, one extending beyond the other and one being of different radius from the other, which projections enter the segmental recesses in the sleeve, and pins passed through 125 the handle centrally with respect to the radius of the projections and through said tongue and said shank, as described.

4. In a wire-stretcher, an upper and a lower jaw, an extension from each of the jaws at an

angle to their gripping-surfaces, the extensions of the upper jaw being loosely passed through the lower jaw to a parallel position with its extensions, a rocking handle normally 5 in the same horizontal plane with the jaws, and pivotal connections between the handle and each of said extensions from the jaws, segmental projections from the handle, in which projections said pivotal connections are 10 located, and a bearing-head fixed to the upper jaw, extending beyond the same and in

the same horizontal plane with the front edges of the upper and lower jaws and handle, as set forth.

In testimony whereof I have signed my 15 name to this specification in the presence of two subscribing witnesses.

BENNETT MYERS.
